UNITED STATES PATENT OFFICE.

JAMES E. DUFFY, OF PHILADELPHIA, PENNSYLVANIA.

NON-REFILLABLE BOTTLE.

No. 851,620.

Specification of Letters Patent.

Patented April 23, 1907.

Application filed July 12, 1905. Serial No. 269,291.

To all whom it may concern:

Be it known that I, JAMES E. DUFFY, a citizen of the United States, residing at Philadelphia, in the county of Philadelphia and State of Pennsylvania, have invented certain new and useful Improvements in Non-Refillable Bottles, of which the following is a specification.

This invention relates to certain new and useful improvements in non-refillable bottles, of which the following is a full, clear, and exact description:

This invention relates more particularly to that class of bottles in which a valve is provided in the neck of the bottle, with suitable means for guarding and preventing the picking thereof by unauthorized persons for the purposes of refilling, and means permitting the primary filling by the proper parties.

Reference will be had to the accompanying drawing forming a part of this specification in which like numerals of reference designate corresponding parts throughout the several views, in which:

Figure 1 is a vertical section, Fig. 2 is a horizontal section taken on the line X—X thereof, Fig. 3 is a top plan view, and Fig. 4 is a detailed view in vertical section of the filling-tube closure.

Reference numeral 1 designates the body portion of the bottle, formed interiorly with an integral vertically extending tubular portion 2, which extends to a point in close proximity to the bottle bottom 3, but leaving a space therebetween to permit the liquid which is inserted into said portion 2 to enter the body portion of the bottle. The upper part of this tubular portion is formed with a flange 4 and with interiorly and downwardly projecting spurs 5 formed integrally with and of the same material as the body portion. Into this tubular portion is inserted a cork 6 of considerable length, being provided with the trade mark of the firm of whose goods are contained in the bottle, which trade mark shows through the said tubular portion. A seal 7 is placed upon the flange 4 of the said tubular portion after the said stopper has been inserted, and completely covers the opening and stopper of the said tubular portion. Owing to the said spurs 5 project-

ing downwardly, mutilation of the stopper 6 will be affected upon any attempt to remove the said stopper.

The bottle neck 8 is formed with a downwardly tapering opening 9 formed in its lower portion with a seat 10 for the reception of a ball valve 11. Above this valve in the wall of the neck opening is formed an annular groove 12 within which is seated a perforated disk 13, being provided with an upwardly projecting stem 14 which passes through and supports an imperforate disk 15, the circumferential edge of which is spaced from the interior wall of the bottle neck. The upper portion of the bottle neck is formed with an annular enlarged portion 16 forming an interior groove within which the said disk 15 is arranged. From the portion 16 the upper portion of the neck tapers inwardly and is formed with an integral perforated top 17 into which is inserted the upper end of said stem 14, and said perforated top 17 is formed with a projecting peripheral bead or flange 18 over which is clamped the usual crown-seal 19, the cork portion 20 of which covers the perforations of the said top 17.

To fill this bottle the material is introduced through the tubular portion 2, after which the stopper is inserted and the seal 7 affixed. To remove the contents from the bottle the crown-seal 19 is removed and the bottle inverted; the liquid thereupon forces the valve 11 from its seat, passes through the perforations of the disk 13, then around the disk 15 and out through the perforations of the top 17.

It will readily be seen that it is impossible to pick the valve as a wire could not be introduced around disk 15 and thence to the valve especially in view of the bead 21 formed in the neck beneath the disk 15.

Of course, I do not wish to limit myself to the details of construction herein set up as various changes may be made without departing from the spirit of the invention.

Having fully described this invention what is claimed to be new and useful, and desired to be secured by Letters Patent, is:

1. A bottle formed in its side with a filling tube, substantially as described

2. A bottle formed in its side with an integral filling tube, adapted to receive a stopper, and projections within the filling tube for engagement with said stopper.
- 5 3. A bottle formed in its side with an interior integral filling tube, adapted to receive a cork, projections in the interior of said filling tube for engagement with said cork, a flange on the upper portion of said filling tube, and a seal arranged on said flange and

covering the upper portion of said filling tube.

4. A bottle formed in its side with a filling tube and provided in its neck with a valve.

In testimony whereof I affix my signature ¹⁵ in presence of two witnesses.

JAMES E. DUFFY.
